COMBINED PRECISION ULTRAMICRO BURETTE AND DIGITAL COUNTER THEREFOR

George G. Goda, New York, N.Y., assignor to Greiner
Scientific Corporation

Filed Mar. 23, 1965, Ser. No. 84,414

Term of patent 14 years

(Cl. D16—2)

FIGURE 1 is a front elevational view of a combined precision ultramicro burette and digital counter therefor showing my new design;

FIGURE 2 is a plan view thereof;

FIGURE 3 is a left end elevational view thereof; and

FIGURE 4 is a right elevational view thereof.
The undisclosed rear portions of the article are substantially plain.

I claim:

The ornamental design for a combined precision ultramicro burette and digital counter therefor, as shown and described.
